his Attorney.

UNITED STATES PATENT OFFICE.

WALTER G. HUMPHREYS, OF OMAHA, NEBRASKA.

FUEL-VAPORIZER.

1,325,850.

Specification of Letters Patent. Patented Dec. 23, 1919.

Application filed September 17, 1917, Serial No. 191,848. Renewed October 27, 1919. Serial No. 333,685.

To all whom it may concern:

Be it known that I, WALTER G. HUMPHREYS, a citizen of the United States of America, residing at Omaha, in the county of Douglas and State of Nebraska, have invented certain new and useful Improvements in Fuel-Vaporizers, of which the following is a specification.

My invention relates to improvements in 10 means for vaporizing the heavier hydrocarbon oils, more particularly kerosene, for use as an explosive fuel in internal combustion engines, wherein the engine exhaust is employed as the required source of heat to 15 super-heat the fuel mixture, and the objects of my improvements are:

First, to provide a most compact and efficient vaporizer, occupying the minimum of space, giving the maximum of heat receiving and heat imparting surfaces and adapted for simultaneous intermediate fitting in both the fuel intake and exhaust ducts of an internal combustion engine.

Second, to combine both heat and impact 25 or impingement in breaking up the liquid condition of the oil, in a device having no loose or operatively movable parts.

Third, to facilitate complete cleaning of the fuel duct throughout its entire length 30 without in any manner disconnecting the vaporizer from the two ducts in which it may be interposed. These with other minor objects hereinafter particularly described, I attain by the structure illustrated in the 35 accompanying drawing in which—

Figure 1 is a sectional view on the broken lines 1 of Figs. 2 and 3; Fig. 2, a sectional view at right angles to the view Fig. 1, and on the broken line 2 of that figure; 40 Fig. 3, a central sectional view on the broken lines 3 of Figs. 1 and 2; and Fig. 4, is an enlarged fragmental sectional view of the interlapping spaced shortened or decurtate partitions forming the sinuous vaporizing fuel duct through the vaporizer. In all of 45 which views the same reference numeral indicates like parts.

For convenience in this description it is assumed that the detachable cover or clean-out plate 13 is on the face or front of the vaporizer, where it is always accessible, that the connected fuel intake pipe is a vertical duct carrying an ascendant current as indicated by the arrows 12 and that the 55 connected exhaust pipe carries a horizon-

tally moving current as indicated by the arrows 5.

The centrally disposed internal fuel-duct chamber, has side and back walls 7 of thin integral cast metal plate to quickly receive, 60 conduct and impart the heat. This chamber is open at top and bottom through the threaded bosses 16 and 16, on the exterior integral top and bottom walls of the vaporizer, for connection with the fuel intake 65 pipe. The front of this chamber is closed by the removable clean-out plate 13. The exterior body wall 17 is disposed from side to side around the back of the fuel-duct chamber and spaced away from the thin 70 walls 7 to form and inclose the flattened exhaust duct 6, surrounding the back and sides of said chamber in a loop as shown. Said exhaust duct terminates at opposite sides in the threaded bosses 15 and 15 for connection 75 with the engine exhaust pipe. The top and bottom ends 18 and 18 are shaped as shown to also integrally form the top and bottom of the fuel-duct chamber. And the front is cast open, to the extent of the inclosed 80 chamber, with the beveled-edged rabbets 19 and 19 at the sides of the opening, to place the cleanout or cover-plate 13, secured by the screws 20.

The fuel-duct-chamber has the decurtate 85 partitions 9, all integrally connected with the back of the chamber and alternately integrally based on opposite side walls of the chamber. These partitions standing with their shortened ends interlapped and spaced 90 apart from the walls of the sinuous fuel duct 8. It is obvious, by noting Fig. 1, that this arrangement of oppositely alternately abridged partitions gives a great 95 length of duct in the small fuel chamber of the vaporizers.

At the side of the base of each partition an inclined ledge 10 is disposed in alignment with the terminal edge of the next successive partition. These ledges stand toward the terminal edges of the next successive partitions, to stricture or reduce the duct to a thin narrow slit or discharging nozzle 11, at the end of each cross lap of the duct, through the chamber. Each of these slit-nozzles delivers a thin sheet of the fuel to strike squarely against the adjacent section of the thin wall 7; which wall, is heated by the exhaust current passing around in the duct 6. These successively repeated im- 110

pingements of thin sheets of the fuel against progressively-approached parts of the hot thin metal walls of the chamber, where the walls are common to both ducts, thoroughly 5 break up, and vaporize the most stubborn heavy hydro-carbon oils. Kerosene or a mixture of kerosene and air for fuel, driven or sucked through this vaporizer, is transformed into a most perfect explosive charge 10 for the engine to which the vaporizer is properly connected.

The beveled cut-away 14, on the back of the decurled edge of each partition, serves to enlarge the duct immediately following 15 each place of impingement of the fuel against the heated plate. This gives more room for the rebound and expansion following the impingement and vaporizing action on the fuel after each slit nozzle is 20 passed.

It is obvious that any irreducible matter that accumulates in the thin slits, is easily raked out of the open ended slit, when the cover plate is removed. Also that the slit 25 may be made so narrow that scarcely any irreducible matter will be passed through to the engine. Also that these slits will not be easily fouled, to a complete stoppage, like the small round or square openings in 30 ordinary strainers.

I claim:

1. A fuel vaporizer, comprising a fuel duct, a heating medium duct, said ducts having a common heat-conducting wall, a 35 series of constrictions in said fuel duct forming a succession of jets disposed throughout the length thereof, to repeatedly discharge the passing fuel against said heat-conducting wall, and portions of the fuel 40 duct immediately following each jet enlarged in area of cross-section.

2. A fuel vaporizer, comprising a fuel duct, a duct adapted to carry a heating medium, said ducts having a common heat-conducting wall, a series of strictures in said fuel duct to form a succession of narrow slits disposed to repeatedly discharge the conducted fuel in thin sheets against said wall. 45

3. A fuel vaporizer, comprising a duct for a heating medium, a fuel duct having a wall common to both ducts, ledges in the fuel duct to form a succession of narrow transverse slots to discharge the conducted fuel in thin sheets against said common wall, and a detachable section of the wall 55 of said fuel duct to laterally open one side thereof and one end of each slot.

4. A fuel vaporizer comprising a heating medium duct of flattened cross-section and longitudinally bent to form the back and 60 connected opposite sides of an inclosure, connected top and bottom inclosure walls having perforations for fuel pipe connections, horizontal decurled partitions, alternately based on opposite side walls, interlapped and spaced flatwise vertically in the inclosure to form a sinuous fuel duct throughout the height thereof, and a detachable front-plate to form the front wall of 65 said sinuous fuel duct. 70

5. A fuel vaporizer, comprising a fuel duct, a heating medium duct, said ducts having a common heat-conducting wall, and a series of constrictions in said fuel duct forming a succession of jets disposed 75 throughout the length thereof, to repeatedly discharge the passing fuel against said heat-conducting wall.

In testimony whereof I have affixed here-to my signature.

WALTER G. HUMPHREYS.
